VALVE FOR FUEL INJECTION PUMPS

Herbert C. Edwards, Massillon, Ohio, assignor to
The Timken Roller Bearing Company, Canton,
Ohio, a corporation of Ohio

Application December 16, 1937, Serial No. 180,122

6 Claims. (Cl. 251—119)

This invention relates to a valve for pumps for the fuel injection systems of compression ignition engines, particularly pumps of the type that terminate the delivery of fuel to the injection nozzle by relieving the pressure in the pump chamber during the pressure stroke of the piston. The principal object of the present invention is to devise a delivery valve for the above type of pump which upon relief of the pressure in the pump chamber, will permit a return flow thereto of fuel in the conduit leading to the injection nozzle, thereby relieving the pressure in said conduit and thus preventing leakage or dribble of fuel from said nozzle. Other objects are simplicity and cheapness of construction and compactness of design. The invention consists in the construction, combinations and arrangements of parts hereinafter described and claimed.

In the accompanying drawings, which form part of this specification, and wherein like symbols refer to like parts wherever they occur,

Fig. 1 is a central longitudinal section through a fuel injection pump provided with a delivery valve embodying my invention.

Fig. 2 is an enlarged central longitudinal section through said pump in the region of the discharge valve;

Fig. 3 is a section similar to Fig. 2 illustrating a modification of the invention; and

Figs. 4 and 5 are views similar to Figs. 1 and 2, respectively, illustrating a further modification of the invention.

In the accompanying drawings, my invention is shown in connection with a pump of the kind used for supplying fuel to the injection nozzle of an internal combustion engine of the compression ignition type. The upper portion of the pump body or housing 1 has a vertical bore therein in which is mounted a cylinder 2 having a head portion 3 supported on an annular seat 4 provided therefor in said bore. The pump cylinder 2 is held down on its seat in the pump housing bore by an outlet fitting 5 that is threaded into the upper end of said bore and has its upper end threaded for connection with a suitable conduit or pipe (not shown) which leads to a hydraulically operated fuel injection nozzle (not shown) for delivering fuel to the combustion chamber of the engine. The outlet fitting 5 is provided near its lower end with a peripheral groove 6 adapted to receive and support a compressible gasket 7 that is held under compression between said groove and the wall of the housing bore and prevents leakage of primary fuel past said fitting.

Mounted for reciprocating movement in the pump cylinder or barrel 2 is a piston 8 which cooperates with said cylinder to form a pressure space or chamber 9 therein at the upper end thereof. The pump cylinder 2 has a radial fuel port 10 therein adapted to establish communication between the pressure space 9 and a fuel chamber or passageway 11 in the pump housing; and the piston 8 is provided with an annular groove 12 which communicates with said pressure space through a longitudinal peripheral groove 13 in said piston.

Clamped between the outer marginal portions of the opposing end faces of the pump cylinder 2 and the outlet fitting 5 is an annular spacer or washer 14. Located in the opening in the washer 14 is a discharge valve 15 preferably in the form of a flexible or resilient disk of metal or other suitable material, which is of smaller diameter than said opening so as to provide an annular space or passageway 16 for fuel between said washer and said disk. This disk has a relatively thick rim or marginal portion 17, which seats on the upper end of the cylinder 2, and a relatively thin middle or body portion 18 that covers the upper end of the piston receiving bore in the cylinder 2 and forms the top wall of the pressure space 9 and is provided with a central circular fuel opening or port 19 adapted to be closed by the adjacent end of the outlet fitting 5.

The valve opposing end of the outlet fitting 5 has an annular groove therein which limits the contact between said end of said fitting and the valve 15 to the ported central portion of the latter and also forms an annular fuel passageway or chamber 20 above said valve that communicates at its outer margin with the annular fuel passageway 16 between said valve and the spacing washer 14. The outlet fitting 5 is also provided with a fuel passageway 21 which leads from the annular chamber 20 to the outer end of said fitting and communicates with and constitutes a part of the supply pipe or conduit for the injection nozzle of the fuel injection system. The spacing washer 14 is preferably made slightly thinner than the rim portion 17 of the discharge valve, whereby the ported central portion 18 of said valve is dished or bowed downwardly by the middle portion of the outlet fitting 5 and is placed under tension sufficient to remain in contact with said fitting and keep the port 19 closed during the suction stroke of the piston.

The modified construction shown in Fig. 3 is similar to that shown in Fig. 2, except that the resilient discharge valve of Fig. 3 is made up of

a plurality of superimposed disks 15a of resilient metal and is supported clear of the upper end of the cylinder on an annular plate 15b, whose outer marginal portion is clamped between the spacing washer 14 and the upper end of said cylinder.

By the arrangement described, the fuel drawn into the pressure space or chamber 9 during the suction stroke of the piston is placed under pressure when said piston, during its pressure stroke, passes above the port 10. During this pressure stroke of the plunger, the central portion 18 of the discharge valve 15 is pressed tightly against the outlet fitting 5, thereby preventing escape of fuel through the port 19 in said valve, while the rim portion 17 of said valve is lifted off its seat on the upper end of the cylinder, thereby permitting the fuel to pass through the annular space 16 between said rim and the spacing washer 14 and thence into the annular chamber 20 above said valve and thence through the longitudinal passageway 21 leading to the fuel injection nozzle. At a predetermined point in the pressure stroke of the piston, the annular groove 12 therein is placed in communication with the port 10 in the cylinder, thereby relieving the pressure in the pump chamber and on the rim portion 17 of the valve, which portion is then forced down on its seat on said cylinder by the greater pressure in the annular chamber 20. This higher pressure of the fuel in the annular chamber and the conduit leading to the closed injection nozzle then operates to force the resilient middle portion 18 of the discharge valve downwardly off its seat on the inner end of the outlet fitting, thereby permitting a return flow of fuel from said conduit through the central port 19 in said valve into the pressure space of the cylinder. This return flow of the fuel reduces the pressure of the fuel in the delivery conduit to a pressure that will enable the injection nozzle to close quickly and tightly and thus prevent dripping or dribbling of fuel therefrom and thereby eliminate preignition or after burning of the fuel in the combustion chamber of the engine.

In the modification shown in Figs. 4 and 5, the outlet fitting 5a has an axial fuel passageway 21a, threads that terminate short of the outer end of the housing bore and a peripheral groove 6a located outwardly of its threads and adapted to receive a compressible gasket 7a. This location of the gasket 7a outwardly of the threaded portion of the housing bore makes it unnecessary to force the gasket through the threaded portion of the bore and thus prevents the gasket from being torn or frayed by said threads.

The discharge valve 15c shown in Figs. 4 and 5 is supported in an annular casing located in the housing bore between the pump cylinder 2 and the outlet fitting 5a. This casing comprises a rim portion 22, which is clamped between the outlet fitting and the cylinder, and a hub portion 23, which is connected to said rim portion by a radial web having openings 24 therein. The valve 15c, which is preferably made up of a series of superimposed disks of resilient metal, has its central portion seated on the upper or outer end of the hub portion 23 of the annular valve casing and provided with a central port 19a of smaller diameter than the diameter of said hub portion. The valve is loosely secured to the valve casing by means of a headed pin 25, which extends through the port 19a with an annular clearance space therebetween and is threaded or otherwise secured to the upper or outer end of the hub por-

tion 23. The valve is of smaller diameter than the inner diameter of the rim portion 22 of the valve casing so as to provide an annular space therebetween; and the marginal portion of said valve is adapted to seat flatwise against the lower or inner end of the outlet fitting 5a around the adjacent end of the fuel passageway 21a therein.

The operation of the modified valve construction shown in Figs. 4 and 5 is as follows: The fuel drawn into the pressure space or chamber 9 during the suction stroke of the piston 8 is placed under pressure when said piston during its pressure stroke passes the port 10. During this pressure stroke of the plunger, the pressure of the fuel against the underside of the valve lifts the ported central portion thereof off its seat on the upper end of the hub portion 23 of the valve casing, thereby permitting the fuel to pass through the axial port 19a in said valve and thence into the axial fuel passageway 21a in the outlet fitting. When the annular groove 12 in the piston registers with the port 10 in the cylinder, the pressure of the fuel on the underside of the valve is relieved and the higher pressure of the fuel in the fuel passageway 21a on the upper surface of the valve then operates to force the marginal portion of said valve off its seat at the inner end of the outlet fitting, thereby permitting a return flow of fuel from said fuel passageway into the pressure chamber of the cylinder. This return flow of the fuel reduces the pressure of the fuel in the delivery conduit, thereby enabling the hydraulically opened injection nozzle supplied thereby to close quickly and tightly and thus prevent dripping or dribbling of fuel therefrom.

Obviously, the hereinbefore described construction admits of considerable modification without departing from the invention. Therefore, I do not wish to be limited to the precise construction shown and described.

What I claim is:

1. A valve construction comprising an inlet chamber, an outlet chamber, valve seats associated with the adjacent ends of said chambers, the inlet chamber valve seat facing the outlet chamber and the outlet chamber valve seat facing the inlet chamber, and a disk valve interposed between said ends of said chambers and having a central ported portion, the marginal portion of one face of said valve and the central ported portion of the opposite face thereof being adapted to seat simultaneously on said inlet and outlet chamber, respectively, to cut off communication therebetween, said valve being flexible whereby one of said marginal and central ported portions of said valve is adapted to be forced off its seat by a pressure in said inlet chamber in excess of that in said outlet chamber, and the other of said portions is adapted to be forced off its seat by a pressure in said outlet chamber greater than the pressure in said inlet chamber.

2. A valve construction comprising an inlet chamber, an outlet chamber, valve seats associated with the adjacent ends of said chambers, the inlet chamber valve seat facing the outlet chamber and the outlet chamber valve seat facing the inlet chamber, and a disk valve interposed between said ends of said chambers and having a central ported portion, the marginal portion of one face of said valve and the central ported portion of the opposite face thereof being adapted to seat simultaneously one on said inlet chamber and the other on said outlet chamber to cut off communication therebetween, said valve being flexible whereby one of said marginal and

central ported portions of said valve is adapted to be forced off its seat by a pressure in said inlet chamber in excess of that in said outlet chamber, and the other of said portions is adapted to be forced off its seat by a pressure in said outlet chamber greater than the pressure in said inlet chamber.

3. A valve construction comprising an inlet chamber, an outlet chamber, valve seats associated with the adjacent ends of said chambers, the inlet chamber valve seat facing the outlet chamber and the outlet chamber valve seat facing the inlet chamber, and a disk valve interposed between said ends of said chambers and having a central ported portion, the marginal portion of one face of said valve and the central ported portion of the opposite face thereof being adapted to seat simultaneously one on said inlet chamber and the other on said outlet chamber to cut off communication therebetween, said valve being flexible whereby said marginal portion of said valve is adapted to be forced off its seat by a pressure in said inlet chamber in excess of that in said outlet chamber, and said central ported portion is adapted to be forced off its seat by a pressure in said outlet chamber greater than the pressure in said inlet chamber.

4. A valve construction comprising an inlet chamber, an outlet chamber, valve seats associated with the adjacent ends of said chambers, the inlet chamber valve seat facing the outlet chamber and the outlet chamber valve seat facing the inlet chamber, and a disk valve interposed between said ends of said chambers and having a central ported portion, the marginal portion of one face of said valve and the central ported portion of the opposite face thereof being adapted to seat simultaneously one on said inlet chamber and the other on said outlet chamber to cut off communication therebetween, said valve being flexible whereby said central ported portion of said valve is adapted to be forced off its seat by a pressure in said inlet chamber in excess of that in said outlet chamber, and said marginal portion is adapted to be forced off its seat by a pressure in said outlet chamber greater than the pressure in said inlet chamber.

5. A valve construction comprising an inlet

chamber, an outlet chamber, valve seats associated with the adjacent ends of said chambers, the inlet chamber valve seat facing the outlet chamber and the outlet chamber valve seat facing the inlet chamber, and a disk valve interposed between said ends of said chambers and having a central ported portion, the marginal portion of one face of said valve and the central ported portion of the opposite face thereof being adapted to seat simultaneously one on said inlet chamber and the other on said outlet chamber to cut off communication therebetween, said valve comprising a plurality of superimposed disks having registering openings forming said central ported portion of said valve, said disks being flexible whereby one of said marginal and central ported portions of said valve is adapted to be forced off its seat by a pressure in said inlet chamber in excess of that in said outlet chamber, and the other of said portions is adapted to be forced off its seat by a pressure in said outlet chamber greater than the pressure in said inlet chamber.

6. A valve construction comprising an inlet chamber, an outlet chamber, valve seats associated with the adjacent ends of said chambers, the inlet chamber valve seat facing the outlet chamber and the outlet chamber valve seat facing the inlet chamber, a disk valve interposed between said ends of said chambers and having a central ported portion, the marginal portion of one face of said valve and the central ported portion of the opposite face thereof being adapted to seat simultaneously on said outlet and inlet chamber, respectively, to cut off communication therebetween and means for loosely securing said central ported portion of said valve to the valve seat for said central ported portion, said valve being flexible whereby the loosely secured central ported portion of said valve is adapted to be forced off its seat by a pressure in said inlet chamber in excess of that in said outlet chamber, and said marginal portion of said valve is adapted to be forced off its seat by a pressure in said outlet chamber greater than the pressure in said inlet chamber.
